UNITED STATES PATENT OFFICE.

WALTER FERRIS, OF MILWAUKEE, WISCONSIN, ASSIGNOR TO BUCYRUS COMPANY, OF SOUTH MILWAUKEE, WISCONSIN, A CORPORATION OF WISCONSIN.

DRUM OR SCREEN DRIVE AND SUPPORTING MEANS.

Application filed February 9, 1922. Serial No. 535,399.

To all whom it may concern:

Be it known that I, WALTER FERRIS, a citizen of the United States, and resident of Milwaukee, in the county of Milwaukee and 5 State of Wisconsin, have invented certain new and useful Improvements in Drum or Screen Drives and Supporting Means; and I do hereby declare that the following is a full, clear, and exact description thereof.

10 My invention relates to new and useful improvements in the means for driving and supporting rotary members such as tumbling drums, separating screens and the like, and has especial reference to separating screens 15 for use on placer dredges.

In the use of such screens it is customary to mount the same at an incline to the horizontal or to the deck of the dredge and to provide independent guide and supporting 20 means for taking up the side and end thrusts at the lower end. It is therefore a primary object of this invention to simplify and improve such supporting means and eliminate a considerable number of heretofore necessary parts by utilizing a means for taking up both side and end thrusts.

It has also been heretofore customary to dispose the axis of the drive shaft of the screen parallel to the axis of the latter and 25 thus at an incline to the dredge deck which necessitated the use of a train of bevel gears or other connecting elements between the motor or like drive machine and the drive shaft. Consequently it is another important 30 object of the invention to provide a drive means which will permit the drive shaft to be disposed parallel with the deck and at an angle to the screen axis to thereby eliminate said bevel gear train or other connections and permitting a direct drive from the 35 motor or the like to the drive shaft.

An additional object of the invention is to provide a friction gear connection between the screen and the drive shaft hereinbefore 40 referred to, the faces of the parts of said friction gear connection being disposed obliquely to the axes of the screen and drive shaft respectively, whereby owing to the inclination of said screen, an effective friction engagement is maintained at all times between these parts.

This invention has for a further object to provide roller members so designed and constructed as to receive both the end and

side thrusts of a rotary member mounted 55 therebetween.

A still further object of this invention resides in the provision of means for procuring the ready adjustment of the thrust rollers longitudinally of the rotary member. 60

With the above and other objects in view which will appear as the description proceeds, my invention resides in the novel construction, combination and arrangement of parts substantially as hereinafter described 65 and more particularly defined by the appended claims, it being understood that such changes in the precise embodiment of the hereindisclosed invention may be made as come within the scope of the claims. 70

In the accompanying drawings, I have illustrated one complete example of the physical embodiment of my invention constructed according to the best mode I have so far devised for the practical application of the 75 principles thereof, and in which:

Figure 1 represents a side elevational view, with parts broken away, of the lower end of a placer dredge screen showing my improved means for receiving both the side 80 and end thrust thereof as well as the means for driving the same;

Figure 2 is a longitudinal sectional view taken on the plane of the line 2—2 of Figure 1 and showing one of the improved supporting means in plan view;

Figure 3 is an end elevational view of the parts shown in Figure 1, and

Figure 4 is a diagrammatic view of a screen and the drive means therefor. 90

In the illustrated application of the invention the reference character S represents a placer dredge screen which is substantially cylindrical throughout its length and open at its opposite ends, the same being 95 mounted so that its axis of rotation is at an incline to the horizontal, or in other words to the plane of the deck of the dredge. While the intermediate portions of this screen are perforated as is customary in 100 placer dredge screens, the ends are imperforate rings, and in the present instance the ring at the lower end is provided with a track annulus A, the same being secured therearound in any desired manner and including two separate parts, an annular friction drive surface a' and an annular guide track a''. 105

At this lower end of the screen S is disposed a suitable supporting framework consisting of upright bars F and F' which are connected below said screen by horizontal bars F², the same in turn supporting horizontal bars F³. The upper portions of the upright bars F and F' are connected on each side of the screen S with a pair of slide rails w, the rails of each of these pairs being spaced apart parallel to each other and inclined similarly to the inclination of the screen. In other words the axis of the latter and said rails w are parallel for a purpose to be hereinafter more particularly set forth.

The bars F³ have bearings B mounted thereon for the reception of the drive shaft K, this shaft having a friction gear C mounted thereon between said bars F³ as well as a spur gear D. As shown in Figure 3 the shaft K is in the vertical plane of the axis of the screen S and the gear C engages the friction drive surface a' of the annulus A, thus supporting to a considerable extent the lower end of the screen S. Although the axis of rotation of the screen S is oblique to the horizontal, the shaft K is journaled horizontally or approximately so, thus enabling the ordinary spur gear D to be readily connected with the drive pinion P of a motor M.

In carrying out this drive connection, the friction drive surface a' is oblique with respect to the axis of rotation of the screen S, or in other words converges toward the lower end of the latter. Likewise the peripheral surface of the friction gear C is oblique with respect to the axis of the shaft K and is converged in a direction similar to the convergence of the surface a'. Thus the inclination of the friction surface a' forming the gear ring of the screen S and the surface of the friction gear C, permit the inclined screen to be readily rotated by a shaft whose axis is substantially horizontal, and at the same time provides an improved and very effective friction engagement.

Owing to the rotation of the screen S, there is necessarily more or less side thrust exerted, and owing to the inclination as well as the weight of the screen S, there will be a very appreciable end thrust at the lower end of the latter. In the present instance both of these thrusts are taken up by means of a pair of thrust rollers R, which are located diametrically opposite each other on opposite sides of the annulus A and engaged with the annular guide track a'' thereof. This track has its face disposed obliquely with respect to the axis of rotation of the screen S, and consequently the axes of the trunnions T of the thrust rollers R are at an angle to the said axis of the screen. The peripheral surfaces of

these rollers are likewise disposed obliquely to their axes as most clearly indicated in Figure 2.

The hereinbefore mentioned slide rails w form supporting means for roller brackets E each of which carries a pair of spaced bracket arms E' between which one of the rollers R is journaled. Each of said brackets E includes a slide plate E² which spans the rails w and is slidably engaged with the inner surfaces thereof, said plate being guided and positioned by lugs e, and held against movement by adjusting means carried by it and the rails w. In other words the opposite sides of the plates E² to those from which the lugs e project are provided with ears h, and these elements receive adjusting screws g (see Figure 2). These screws g project from opposite sides of the plates E² parallel to the rails w and are extended through brackets f carried by the latter, these screws being fixed to the brackets by clamp nuts d.

As the result of such an arrangement the diametrically arranged thrust rollers R receive both the end thrust and side thrusts of the screen S. Furthermore the proper adjustment of the rollers R with respect to the inclined guide track a'' is readily carried out by the simple shifting of the brackets E which, after adjustment, are rigidly locked in position by the adjusting screws g and their lock nuts d.

Obviously many different arrangements of parts and changes in the construction thereof may be employed for carrying out these features, as well as the driving means for the screen S, without departing from the principles of the invention or sacrificing any of its advantages.

I claim:

1. In a mechanism of the class described, a member rotatable on a predetermined axis and urged in one direction longitudinally of said axis, an annular guide track carried by the member, said track having a bearing face disposed obliquely of said axis, a stationary thrust roller mount disposed adjacent the track, a thrust roller journaled in the mount and engaging the track face, and means for adjusting the mount parallel to the axis of the rotatable member to move the roller toward and away from the track face, said roller receiving the side and end thrusts of the member.

2. In a mechanism of the class described, a member rotatable on a predetermined axis and urged in one direction longitudinally of said axis, an annular guide track carried by the member, said track having a bearing face disposed obliquely of said axis, a stationary thrust roller mount disposed adjacent the track, a thrust roller journaled in the mount on an axis extending obliquely of the first mentioned axis and engaging the

oblique track face, and means for moving the mount substantially parallel to the first mentioned axis to adjust the engagement between the track face and the periphery of 5 the roller, said roller receiving both the end and side thrusts of the member.

3. In a mechanism of the class described, a member rotatable on a predetermined axis and urged in one direction longitudinally of 10 said axis, an annular guide track carried by the member, slide rails disposed adjacent said track, a slide plate shiftable on said rails, means for holding the plate in adjusted positions on the rails, and a thrust 15 member carried by the plate for engaging the end of the track.

4. In a mechanism of the class described a member rotatable on a predetermined axis and urged in one direction longitudinally 20 of said axis, an annular guide track carried by the member, a pair of spaced parallel slide rails disposed adjacent the track, a slide plate spanning the rails and shiftable thereon, guide lugs projecting from the 25 plate between the rails and engaging the same, means for adjusting the plate longitudinally of the rails and for holding the same in adjusted positions, and a thrust member carried by the plate for engaging 30 the annular track.

5. In a mechanism of the class described, a member rotatable on a predetermined axis and urged in one direction longitudinally of 35 said axis, an annular guide track carried by the member, said track having a bearing face disposed obliquely of said axis, a pair of spaced parallel slide rails disposed adjacent the track and parallel with said axis, a slide plate spanning the rails and shiftable thereon, means for adjusting the plate longitudinally of the rails and parallel to 40 said axis, and a thrust roller journally carried by the plate and mounted on an axis extending obliquely of the first mentioned 45 axis, said roller having its periphery engaged with the oblique track face and receiving both the end and side thrusts of the member.

6. In a mechanism of the class described, a member rotatable on a predetermined axis, 50 an annular track carried by said member, diametrically opposed thrust rollers having their peripheries engaged with the track, and a main roller positioned beneath the rotatable member and having its periphery engaged with the track to support the weight 55 of the rotatable member.

7. In a mechanism of the class described, a member rotatable on a predetermined axis, an annular track carried by said member, 60 diametrically opposed rollers having their peripheries engaged with the track to receive both the side and end thrusts of the rotatable

member, a main roller having its periphery engaged with the track and supporting the weight of the rotatable member, and means 65 for rotating the main roller.

8. In a mechanism of the class described, a member rotatable on a predetermined axis and urged in one direction longitudinally of 70 said axis, an annular guide track carried by the member, said track having a bearing face disposed obliquely of said axis, a friction gear mounted beneath the member and having its periphery engaged with the track face to support the weight of the member, 75 and means for rotating the friction gear, the angle between the track face and said axis being such that the urging of the member longitudinally in one direction increases the frictional engagement of the friction gear 80 with the track face.

9. In a mechanism of the class described, a member rotatable on a predetermined axis and urged in one direction longitudinally of 85 said axis, an annular guide track carried by the member, said track having substantially flat bearing faces disposed obliquely of each other and of said axis, diametrically opposed rollers having their peripheries engaged with one track face to receive both the side 90 and end thrusts of the member, a friction gear having its periphery engaged with the other track face and supporting the weight of the member, the angle between the track face engaged by the friction roller and said axis being such that end thrust in one direction increases the frictional engagement 95 between the friction gear and said track face, and means for rotating the friction gear.

10. In a mechanism of the class described, a member rotatable on a predetermined axis, and an annular track carried by the member and having a bearing face engageable with the periphery of a thrust roller for receiving both the end and side thrusts of the 100 member and a bearing face engageable with the periphery of a member weight supporting roller.

11. In a mechanism of the class described, a member rotatable on a predetermined axis, 110 and an annular track carried by the member and having a bearing face disposed obliquely of said axis and engageable with the periphery of a roller for receiving both the end and side thrusts of the member and a bearing face disposed obliquely of the first named bearing face and said axis and engageable with the periphery of a friction gear for supporting the weight of said member.

In testimony that I claim the foregoing I 120 have hereunto set my hand at Milwaukee, in the county of Milwaukee and State of Wisconsin.

WALTER FERRIS.
